UNITED STATES PATENT OFFICE.

MAX SCHWENDNER, OF READING, PENNSYLVANIA, ASSIGNOR TO THE
READING HARDWARE COMPANY, OF PENNSYLVANIA.

DESIGN FOR AN ESCUTCHEON-PLATE, &c.

SPECIFICATION forming part of Design No. 28,410, dated March 29, 1898.

Application filed January 24, 1898. Serial No. 667,830. Term of patent 7 years.

To all whom it may concern:

Be it known that I, MAX SCHWENDNER, a citizen of the United States of America, and a resident of Reading, county of Berks, State of Pennsylvania, have invented and produced a new and original Design for Escutcheon-Plates and Similar Articles of Builders' Hardware, of which the following is a specification.

The drawing is a perspective view of an escutcheon-plate, showing my design.

The leading feature of my design is the configuration of the base-plate, consisting in a general rectangular shape bordered by straight side edges *a* and *b* and top and bottom edges *c*

and *d* of double ogee outline, openings *ee* being formed between said ogees and extending inward, as shown, with lateral branches bounded by intersecting curves.

What I claim is—

The design for an escutcheon-plate or similar article of builders' hardware substantially as shown and described.

Signed by me at Reading, Pennsylvania, this 20th day of January, 1898.

MAX SCHWENDNER.
